Primary Examiner — Darlington Ly*Assistant Examiner* — Giang Hoang Tran(74) *Attorney, Agent, or Firm* — Frost Brown Todd LLP(57) **CLAIM**

The ornamental design for an all-terrain vehicle as shown and described.

DESCRIPTION

FIG. 1 is a front elevation view of an all-terrain vehicle;

FIG. 2 is a rear elevation view thereof;

FIG. 3 is a left side elevation view thereof;

FIG. 4 is a right side elevation view thereof;

FIG. 5 is a top plan view thereof;

FIG. 6 is a first perspective view thereof; and,

FIG. 7 is a second perspective view thereof.

Broken lines show portions of the all-terrain vehicle that form no part of the claimed design.

1 Claim, 7 Drawing Sheets(56)
